CARRIAGE RETURN MECHANISM FOR
ACCOUNTING MACHINES

Walter A. Anderson, Bridgeport, Conn., assignor
to Underwood Elliott Fisher Company, New
York, N. Y., a corporation of Delaware

Original application September 25, 1936, Serial
No. 102,517. Divided and this application No-
vember 22, 1940, Serial No. 366,531

2 Claims. (Cl. 197—66)

This invention relates to accounting machines, and more particularly to the means for returning the traveling paper carriages, commonly employed on such machines.

This case is a division of my application Serial No. 102,517, filed September 25, 1936, now Patent No. 2,274,575, issued February 24, 1942.

One of the objects of this invention is to return the paper carriage to a position farther to the right than the position to which it is normally returned, upon the depression of a special return key on the keyboard.

With this and incidental objects in view, the invention consists in certain novel features of construction and combinations of parts, the essential elements of which are set forth in appended claims, and a preferred form of embodiment of which is hereinafter described with reference to the drawings which accompany and form part of the specification.

In said drawings:

Figure 1 is a perspective view of the machine, Figure 2 is a diagrammatic view of the keyboard,

Figure 3 is a front left perspective of the connections for returning the carriage by the full return key,

Figure 4 is a left rear bottom perspective showing details of certain of the parts shown in Figure 3,

Figures 5, 6 and 7 show details of certain parts shown in Figure 3, and

Figure 8 is a front elevation of the carriage return rack and its cushioning mechanism.

This invention is illustrated on a machine of the type disclosed in U. S. Patent No. 2,194,270, issued to Oscar J. Sundstrand on March 19, 1940, to which reference should be made for all details not fully disclosed herein or in my parent application.

Referring to Figure 1, the traveling paper carriage 24 is mounted on suitable guides for lateral movement on the machine. The carriage is moved from right to left by the customary spring motor (not shown). It is moved to the right by a carriage returning mechanism to be described. The carriage supports a control plate 75 carrying magazines 74, the forward ends of which (see Figure 3) strike a tabulating escapement lever 123 to arrest movement of the carriage in its various columnar positions while the carriage is moving from right to left during the working stroke. When the carriage reaches a predetermined position at the end of its travel to the left, the returning mechanism becomes ef-

fective automatically to return the carriage to the right. This mechanism will now be described.

Referring to Figure 3, a shaft 97 is rotated in the direction of the arrow by an electric motor (not shown). A sleeve 98 is fitted in a reduced portion 101 of shaft 97 and is slideable thereon vertically. A pin 102 extending through shaft 97 projects into a slot cut in sleeve 98 to insure rotation of the sleeve with the shaft. One or more teeth 103 are provided on the upper end of sleeve 98 to act as one part of a clutch. A pinion 104 is journaled on a further reduced portion 105 of shaft 97 and engages rack teeth 106 on a bar 107 (see also Figure 4) rigidly secured to the traveling carriage. Teeth 108 on the bottom of the hub of pinion 104 lie in position to be engaged with teeth 103 when the latter are raised into the horizontal plane thereof so that pinion 104 may be driven with shaft 97 and sleeve 98 to return the carriage to its right hand position. This mechanism is substantially the same as disclosed in the above mentioned patent.

The means for raising sleeve 98 so that teeth 103 and 108 may engage to return the carriage includes an engaging block 111 secured on a bar 112 (see also Figure 4) carried under bar 107. A three-arm bell crank 113 is journaled on a stud 114 extending from the machine frame. An arm 115 on the bell crank lies normally in the path of block 111. A blade 116 extending from another arm of the bell crank lies within a groove in sleeve 98. The third arm 117 of the bell crank cooperates with a spring pressed detent 118. When the carriage reaches the end of its leftward movement, block 111 rocks bell crank 113 counter-clockwise by contact with arm 115, and thereby engages the clutch. The rotation of shaft 97 and sleeve 98 then returns the carriage to the right.

A block 121 secured to bar 112 has a flange 122 lying in the path of arm 115. As the carriage moves to the right, flange 122 strikes arm 115 and thereby returns bell crank 113 to the position shown in Figure 3. This disengages the clutch and allows the carriage spring motor to draw the carriage an increment to the left until the forward end of one of the magazines 74 (Figure 3) strikes the tabulating escapement lever 123. Detent 118 is effective to retain bell crank 113 in either of its moved positions.

Means is also provided to return the carriage either from an intermediate position or its left hand position to a position farther to the right

than the position to which it is normally returned. This movement will be termed "a full return," and this position the "fully returned" position. The means for moving the carriage to its fully returned position includes a full return key 124 (Figure 3) secured to a shaft 125. An arm 126 secured to the left end of shaft 125 lies behind a pin 127 secured in an arm 128 mounted on the left end of a shaft 131. A spring 132 tensions arm 128 to the rear. A link 133 embraces pin 127 and is supported for sliding movement on a stationary pin 134. An upward projection on the rear end of link 133 is notched to embrace bell crank 113. By these connections, depression of the full return key 124 allows spring 132 to push link 133 and bell crank 113 to the rear, the latter sliding on its pivot stud 114. When bell crank 113 reaches its rear position, detent 118, resting normally on a surface 135 (Figure 6) of arm 117, drops 20 on a surface 136, holding bell crank 113 in its rear position.

An arm 137 extending downwardly from key 124 oscillates a lever 138 to move a link 141 forward to release the machine for operation when the full return key is depressed. This mechanism operates the same way as disclosed by depression of key 919 in the above mentioned patent.

When bell crank 113 is in its rear position, it 30 lies in the path of a spring pressed detent 142 on a block 143 secured to bar 112, and still lies in the path of block 111. If the full return key is depressed with the carriage in a position where block 143 is to the right (Figure 3) of bell crank 113, tabulation of the carriage at the end of the ensuing cycle resulting from depression of the full return key causes detent 142 to oscillate bell crank 113 to engage the clutch. The rearward movement of bell crank 113 carries its arm 115 out of the path of flange 122 and into the path of the cut out or slotted portion at the rear thereof, the parts being in the position illustrated in Figure 4. Therefore, the carriage will return to the right until a flange 144 on another block 145 secured to bar 112 strikes arm 115 to disengage the clutch. This brings the carriage to its fully returned position.

If the full return key is depressed when the carriage is in a position where the block 142 is to the left (Figure 3) of bell crank 113, the carriage will not be returned immediately but will continue its working stroke until block 111 operates bell crank 113 to initiate the return movement. As before, the cut out portion of block 121 passes over arm 115 and allows flange 144 to disengage the clutch.

Depression of the full return key, as explained above, causes detent 118 to fall on surface 136 of arm 117. This position of the parts is illustrated in Figure 7. Bell crank 113 is thereby held in its rear position until one of the engaging blocks 111 or 143 moves bell crank 113 counter-clockwise. Detent 118 then rests on a surface 146 (Figure 6). When the bell crank is thereafter rocked clockwise to its initial position by flange 144, detent 118 is restored to surface 135. The bell crank 113 is now free to return to its forward position by the tension of a spring 147 (Figure 3).

A more detailed explanation of this mechanism, together with the manner in which key 124 is returned to its raised position, is disclosed in connection with key 919 in the above mentioned patent.

To relieve the shock caused by the weight of the carriage when blocks 111 or 143 strike arm 115, a cushion is provided between these blocks and the carriage. As explained above, these blocks are secured to a bar 112 carried under the bar 107. Bar 112 is slidably supported in two mountings 148 (Figure 8), only one of which is shown, and is tensioned to the left by a spring 152 connected to bar 107 and bar 112. Leftward movement of bar 112 is limited by a forwardly extending projection 153 on the extreme right end of bar 112 contacting a post 154 extending downwardly from bar 107. When the carriage tabulates to the left, and block 111 or 143 strikes arm 115, the carriage continues a short distance to the left, stretching spring 152 and thereby relieving the shock.

While the form of mechanism herein shown and described is admirably adapted to fulfill the objects primarily stated, it is to be understood that it is not intended to confine the invention to the one form of embodiment herein disclosed for it is susceptible of embodiment in various forms all coming within the scope of the claims which follow.

What is claimed is:

1. In a machine of the class described, a traveling paper carriage, a carriage return mechanism, means on the carriage to initiate operation of the carriage return mechanism, additional means on the carriage to terminate operation of the carriage return mechanism, said initiating and terminating means defining the ends of two separate ranges of travel for the carriage with one end of each range overlapping the other, the terminating means defining the end of one of said ranges being slotted and having a portion normally in line with a part of the return mechanism, and means adapted to be manually set to move said part into the path of the slot in said last mentioned terminating means to allow the return mechanism to move the carriage beyond the confines of one range of travel into the other.

2. In a machine of the class described, a traveling paper carriage, a carriage return mechanism, means on the carriage to initiate operation of the carriage return mechanism, additional means on the carriage to terminate operation of the carriage return mechanism, said initiating and terminating means defining a normal range of travel and another separate range of travel, said other range being laterally offset from and having one end thereof overlapping one end of the normal range, a part of the return mechanism normally lying in the path of movement of the terminating means of each range, the terminating means of the normal range having a slot therein, and means adapted to be manually set to move said part of the return mechanism into the path of the slot in the terminating means to allow the return mechanism to move the carriage out of the normal range into the other range.
